UNITED STATES PATENT OFFICE.

WILLIAM D. MILLER, OF SPRINGFIELD, OHIO.

IMPROVEMENT IN CULTIVATORS.

Specification forming part of Letters Patent No. 148,839, dated March 24, 1874; application filed October 20, 1873.

To all whom it may concern:

Be it known that I, WILLIAM D. MILLER, of Springfield, in the county of Clarke and State of Ohio, have invented a new and useful Improvement in Cultivators; and I do hereby declare the following to be a full, clear, and exact description of the same, reference being had to the accompanying drawings, in which—

Figure 1 is a perspective view of my invention. Fig. 2 is a side elevation of the same. Fig. 3 is an elevation of one of my inner plows. Fig. 4 is a perspective view of my clevis detached. Figs. 5, 6, and 7 represent in diagram the method of determining the configuration of my plows, Fig. 7 being a cross-section on line *x x*.

This invention relates to that class of cultivators known as walking straddle-row cultivators; and it consists, first, in the method of coupling the plow-beams to the wheel-frame, and in the method of attaching the draft; second, in the method of constructing the wheel-frame.

That others may fully understand my improvement I will particularly describe it.

The wheel-frame is composed of two metallic bars, A and B. The bar A I prefer to make of round iron. Its two ends are bent in line to form axles for the wheels C C. Its central part is bent upward to a height sufficient to clear the tops of the plants to be cultivated, and it is horizontal for a space of about twelve inches at its highest part, midway between said wheels. The bar B may be made of flat iron, and in strength inferior to the bar A, because it acts mainly as a brace to said bar A. Its central part is horizontal, and in height from the ground about the same as the highest part of bar A. These two bars are riveted together at their points of intersection, as shown in the drawings, and they are connected at top by the tongue or pole D, which is pivoted to the bar B, and clamped fast to bar A, so as to be adjustable thereon; and for this purpose I think a hook-headed bolt, E, with a thumb or lever clamping-nut, is the most convenient. Braces F connect the ends of bars A B, so that a truss or X-frame is constituted, possessing great strength with a comparatively small quantity of material. The bar B, at its ends, is bifurcated, as shown at G, for the purpose

of admitting the shank of the clevis H, to which the front end of the drag-bar or plow-beam I is hinged. The clevis H is adjustable up or down in the slot of the bifurcated end G, so that the draft of the plows may be regulated; and it is also constructed so that the plow-beam is adjustable therein laterally. The vertical position of the clevis in the slot of G may be secured by a pin or bolt. The plow-beam I is double, and to each separate part, *i. j.*, plows (K L) are secured. The beams I, at opposite sides of the machine, are connected together by arch-pieces M M, which are united at their tops, and adjustable thereby by means of a pin or bolt, *m*, and a series of holes through either of which said pin may be inserted, and to distend the arch and keep the plows at a proper distance a spreader, N, with slotted ends, is employed. The said arch-pieces pass through the slots in the ends of the spreader N, and are adjustably secured therein by means of pins *n n*.

By these devices the plows may be readily set and maintained at any desired relative distance from each other, and also so that the plows on one or the other side will run nearer to the plants, if so desired.

The single-tree is attached directly to the clevis H, so that the draft-strain comes immediately upon the plows, and not at all upon the wheel-frame, and therefore I am enabled to make said frame comparatively light, and as the clevis H is free to move forward and backward in the slots G, through a limited space, they act as eveners to prevent undue strains in case one horse shall move a little faster than the other.

The tongue-pole D serves only to steer or direct the general course of the machine, and may be adjusted either directly in the line of advance, or a little obliquely thereto, as may be desirable, to suit a lead-horse which has been trained to walk very near to the row of plants. A guide-lever, P, is jointed to the rear end of the tongue D, and also to the spreader N, preferably passing through a slot therein, and attached by means of a pivot-pin, as shown in the drawing. Said lever is bent sidewise, so that the attendant who walks between the rows of plants may have said lever convenient to his hand, and may thereby guide the shovels

to the right or left, as may be necessary, on account of slight irregularities in the row of plants, or in the conduct of the team. The shovels being adjusted at the proper distance apart, it will only be necessary for the attendant to watch that shovel which is nearest the plants, on one side, as the movement of the opposite shovel will be coincident with the movement of the shovel which he watches. The front end of lever P is pivoted to a T-plate, Q, whereupon it may be adjusted toward one side or the other, to cause the rear end of said lever to project more or less toward the attendant's side of the machine, as may be required for the convenient management of the shovels.

When the cultivator is being transported from place to place, or when turning at the corners, it is required to lift the shovels from the ground, and I therefore place at the rear end of the tongue a saddle, R, upon which the lever P may be rested, and the plows thereby sustained above the ground.

The plates for the shovels K L are formed between proper dies fashioned to produce the configuration described. The inner shovel L may have a portion of its inner edge cut away as shown, so that the soil will not be thrown toward the tender plants to injure them.

When the plants have attained sufficient

growth to be uninjured by the falling of soil upon them, these shovels may be transposed, or others, like shovels K, may be substituted.

Among the advantages of my improvements are, adjustability of the draft-pole or tongue, strength and lightness of wheel-frame, rigid connection of plows on opposite sides of plant row, direct draft upon plow-beams, &c.

Having described my improvements, what I claim as new, is—

1. In combination with the bar A, the bar B, braces F F, and tongue D, to form a trussed wheel, framed as set forth.
2. In a straddle-row cultivator, the plow-beams I I, constructed and combined with the wheel-frame A B, and clevises H H, receiving their draft independent of each other and of said wheel-frame, as set forth.
3. In combination with the slotted bar B and the plow-beam I, the adjusting-clevis H, for the purpose substantially as set forth.
4. In combination with the plow-beams I I, the adjusting-arch M M, with the spreader N, substantially as set forth.

5. In combination with the arch M, the lever P, and saddle R, for the purpose set forth.

WM. D. MILLER.
